UNITED STATES PATENT OFFICE

JOHN HAHN, OF DECATUR, ILLINOIS, ASSIGNOR TO H & W KITE CO., OF DECATUR, ILLINOIS, A CORPORATION OF ILLINOIS

KITE

Application filed October 1, 1931. Serial No. 566,362.

This invention relates to kites. The type of kite forming my invention is of a "knock-down" variety which is easily assembled and which, when to be stored or transported, can be collapsed in such a way as to occupy an exceedingly small space.

The kite of this type most commonly used comprises generally a vertical frame member and a cross frame member near the upper 10 end thereof and secured thereto by some binding means such as rubber bands or resilient wire loops. The substantially triangularly-shaped face of the kite made from paper or fabric is bound at its edges by a 15 cord which is engaged by notches at the ends of the frame members, thereby holding the face stretched over said framework.

There are serious objections to this construction which result in distortion of the 20 kite under the pressure of flight and in many instances breakage of the frame members and tearing of the paper or fabric face. The reasons for this are apparently due to slippage of the cross frame member on the main 25 or vertical frame member and too little rigidity of the main or vertical frame member, which must be of proper weight and size. At the same time, the fact that the face of the kite is too loosely held and in flight is not 30 correctly supported by the framework, does not aid in maintaining an operable device.

My invention is designed to overcome the aforementioned disadvantages and has for its more important objectives, the providing 35 of a kite which can be easily assembled and when dismantled will occupy a small amount of space; which will not become distorted under the pressure exerted thereon when in flight; and which due to its sturdy construction will undergo severe usage and be of lasting qualities.

A further important feature of my kite is the novel means by which the vertical or main frame member and cross frame member 45 are clamped together to prevent slippage therebetween and yet allow folding of the frame members into alignment for storage and transportation purposes. Such novel clamping means aids also in preventing distortion of the kite as a whole.

With these and other objects and advantages in mind, attention is directed to the drawings in which:

Figure 1 is a top plan view of the kite.

Figure 2 is a sectional view of the kite 65 taken on the line 2-2 of Figure 1.

Figure 3 is an enlarged detailed top view of one of the corner portions of the kite.

Figure 4 is a sectional view of the corner portion taken on the line 4-4 of Figure 3. 60

Figure 5 is a top view of the corner portion of the kite illustrating a modified means for attaching the cords to the frame members.

Figure 6 is a view of the kite when dismantled and ready for packaging for storage or transportation. 65

Figure 7 is a sectional view of the clamp taken on the line 7-7 of Figure 1, looking in the direction of the arrows. 70

Figure 8 is a perspective view of the clamp.

Figure 9 is an enlarged top plan view of the clamp.

Figure 10 is a perspective view of a modified form of clamp. 75

Figure 11 is an enlarged detailed top view of the topmost portion of the kite.

Referring more particularly to the drawings in which like numbers indicate like parts, the kite comprises generally the vertical frame member 1, the cross frame member 2, the face 3 and the clamp 4, which positions the frame members relative to each other. 80

The face 3 which may be composed of suitable paper or fabric is substantially triangular in shape and is bounded by a cord 5 secured by the turned over edges 6 attached thereto in any suitable manner, such as by adhesive. The cord protrudes at the corners of the kite face to form loops 7 as shown in Figure 3, or extensions 8 having a knot 9 as shown in Figure 5. 85

The turned over edges aid in strengthening the face of the kite and attention is called to the reinforcements at the corners thereof, consisting in first turning in and fastening said corners as at 10, and then again turning in and fastening said corners 90 95 100

as at 11, before the edges 6 are turned over and themselves fastened, as shown in Figure 3.

The top of the kite adjacent the upper end 5 of the vertical frame member is usually the weakest point of the face and consequently most likely to tear. In order to strengthen this point I provide at the top of the kite a reinforcing means comprising a short piece 10 of cord 20 positioned at the extreme edge of and beneath the turned over portion 21 which is again turned over as at 22 to form a continuation of the turned over edges 6 as shown in Figure 11.

15 Such arrangements doubly reinforce the corners and top of the kite which are subjected to the greatest strains and which, when repeatedly assembled and dismantled, will tear unless sufficiently reinforced as disclosed in my invention.

The vertical or main frame member 1 is set upon its edge and protrudes slightly beyond the top and bottom of the kite face. The paper or fabric is secured to the sides 25 12 and lower edge 13 of the said frame member in any suitable manner such as by adhesive.

30 It will be observed that by such construction the face of the kite is equally divided by the vertical frame member and it is not necessary to depend entirely upon the fastenings of the face corners to the ends of the frame members by means of the cord loops in order to maintain the face and framework 35 properly positioned relative to each other.

By placing the vertical frame member on its edge, greater rigidity is provided, and the use of a frame member of less weight than usual is possible.

40 The cross frame member 2, when the kite is in assembled position, is at right angles to the vertical frame member at the proper point near the top thereof and held by means of my novel clamping means which will later 45 be described.

Both of the frame members have their ends notched, as shown at 14 in Figures 3 and 4 to accommodate and engage the cord loop 7 or extensions 8 and knot 9.

50 In order that the two frame members may be bound together and be correctly positioned relative to each other at all times without slippage and consequent distortion of the kite, a clamp designated as a whole 55 at 4 is provided, as more particularly shown in Figures 7 to 10 inclusive.

The clamp has the double function of binding the frame members together and allowing the cross member to be turned to an aligned position at the upper edge of the vertical member in order that the framework may be rolled in the face of the kite as shown in Figure 6, and subsequently packaged for storage or transportation.

60 65 The clamp comprises broadly lower loop

members 15 and an upper loop member, the central top portion 16 of which is substantially diagonally positioned above the lower loop members and having end portions 17 which extend beyond and are substantially parallel to the lower loop members.

70 Within the lower loop member 15 is positioned and held on its edge the main or vertical frame member. Within and 75 encompassed by the upper loop member is the cross frame member. It will be noted that the upper loop member is somewhat wider than the cross frame member and when in assembled position, which is at right angles 80 to the vertical frame member, it will be held in such position by the end portions 17 which are contiguous to said cross frame member on both sides thereof as shown in Figure 9.

85 The cross frame member can be partially revolved within the upper loop member in order to be aligned with the vertical frame member when dismantled for packaging purposes.

90 The frame members, while substantially of the same size, usually vary, and allowance for this must be made in the clamping means. It will be observed that due to the construction of my clamp, frame members which vary from the specified size can be inserted 95 into and encompassed by the clamp without difficulty.

When the kite is assembled and the frame members are at substantially right angles to each other, there is no possibility of slippage therebetween. The vertical frame member is tightly held within the lower loop members of the clamp and the cross frame member is tightly held by the upper loop member so that movement by either of the frame members is eliminated. It will be observed that a rigid framework is thus presented and due to the fact that the face of the kite is bisected vertically by the main frame member and is attached thereto, said 100 face will at all times be correctly positioned relative to the framework and there will result no distortion of the kite.

105 In Figure 10 there is disclosed a modified form of the clamp which comprises placing indentations 18 in the top portion 16 of the upper loop member. By means of these indentations, projections 19 are formed which will make engageable contact with the cross frame member and, in so doing, aid in maintaining the cross frame member properly positioned relative to the vertical frame member without the possibility of slippage. The modified form of the clamp is also important, 110 in that because of the indentations, the upper loop member may be made somewhat larger than the clamp shown in the main frame. An advantage is obtained by making the upper loop member somewhat larger 115 than the specified size of the cross frame 120 125 130

member, in that, if the latter varies in size to such an extent that it is impossible to insert the same in the usual form of clamp, insertion will be possible in the modified form of clamp. When the cross frame member is in assembled position or at right angles to the vertical frame member, the two projections 19 will engage the cross frame member and hold the same without slippage. 5 If only one of the projections 19 engage the cross frame member as is the case when it is in aligned position with the vertical frame member, then said cross frame member may be rocked or pivoted on one of the projections 10 19, and even though it is considerably larger in thickness than the distance between the projections and the vertical frame member, it can be moved back and forth in the spaces between the projections to be assembled or 15 dismantled.

To assemble the kite, it is necessary only to unwrap the face thereof from the position shown in Figure 6, revolve the cross frame member within the upper loop member of 20 the clamp to a position at right angles to the vertical frame member, and slip the cord loops or ends with knot into the notches at the ends of the frame members.

A rigid kite structure is, in this way provided, which is of lasting and serviceable quality.

It is obvious that there are various changes and modifications in my invention which are within the spirit and scope of the appended 35 claims.

I claim:

1. In a kite, a face, a main frame member, a cross frame member, and a clamp comprising lower loop members and an upper loop 40 member to bind said frame members in assembled position to prevent slippage thereof and to allow the cross frame member to be aligned with the main frame member when dismantled.

2. In a kite, a face, a main frame member, a cross frame member, and a clamp comprising lower loop members and an upper loop member diagonally arranged thereabove to bind said frame members in assembled position to prevent slippage thereof and to allow the cross frame member to be aligned with the main frame member when dismantled.

3. In a kite, a face, a main frame member positioned on its edge, a cross frame member, and a clamp comprising lower loop members and an upper loop member diagonally arranged thereabove to bind said frame members in assembled position to prevent slippage thereof and to allow the cross frame member to be aligned with the main frame member when dismantled.

4. In a kite, a face, a main frame member positioned on its edge and secured on at least 65 two of its edges to said face, and a clamp

comprising lower loop members to hold the main frame member and an upper loop member diagonally arranged thereabove to encompass and hold the cross frame member when in assembled position.

70

5. A clamp for use with the frame members of a kite having lower loop members and an upper loop member substantially diagonally positioned relative to the lower loop members to prevent slippage of the frame 75 members relative to each other when in substantially assembled position.

6. A clamp for use with the frame members of a kite having lower loop members and an upper loop member substantially diagonally arranged thereabove, the outer ends 80 of said upper loop member forming extensions angularly disposed thereto, said loop members preventing slippage of the frame members relative to each other when in substantially assembled position.

85

7. A clamp for use with the frame members of a kite having lower loop members and an upper loop member substantially diagonally arranged thereabove, the outer ends 90 of said upper loop member forming extensions angularly disposed thereto and parallel to the lower loop members, said loop members preventing slippage of the frame members relative to each other when in substantially assembled position.

95

8. In a kite having frame members, a clamp having lower loop members to engage and hold one of said frame members and an upper loop member to engage and hold the other of said frame members when in substantially assembled position, said upper loop member being substantially diagonally positioned relative to the lower loop members to allow movement of one of the frame members for 100 alignment with the other of the frame members.

105

9. A clamp for use with the frame members of a kite having lower loop members and an upper loop member, the top portion of the 110 latter being provided with projections engaging one of said frame members to prevent slippage thereof relative to the other of said frame members when in substantially assembled position, said upper loop member being 115 circumferentially larger than the frame members.

115

10. In a kite, a face having a reinforcement at its top comprising a piece of cord positioned beneath a turned-in portion, a 120 main frame member positioned on its edge, a cross frame member, and means to bind said frame members in assembled position to prevent slippage thereof, the length of said cord being substantially less than the length of 125 said turned-in portion.

125

11. In a kite, a face having a reinforcement at its top comprising a piece of cord positioned beneath a turned-in portion, said 130 turned-in portion again turned in at the ends

130

of the cord, a main frame member positioned on its edge, a cross frame member, and means to bind said frame members in assembled position to prevent slippage thereof.

5 12. In a kite, a face having a reinforcement at its top comprising a relatively short piece of cord positioned beneath a turned-in portion, said turned-in portion again turned in at the ends of the cord, a main frame member positioned on its edge, a cross frame member, and means to bind said frame members in assembled position to prevent slippage thereof.

10 13. In a kite, a face of substantially triangular configuration bounded by a cord and having reinforcements at its corners and top, the former comprising two turned-in portions one upon the other and the latter comprising a piece of cord positioned beneath a turned-in portion, said turned-in portion again turned in at the ends of the cord, a main frame member positioned on its edge, a cross frame member, and means to bind said frame members in assembled position to prevent slippage thereof.

15 14. A clamp for use with the frame members of a kite having lower loop members and an upper loop member encompassing the frame members respectively to prevent slippage of the frame members when at substantially right angles to each other in assembled positions and allow slippage of the frame members when substantially parallel to each other in unassembled positions.

20 30 35 15. In testimony whereof I affix my signature.

JOHN HAHN.
